CLAMPING MEANS FOR FLARING TOOLS
OR THE LIKEGeorge E. Franck, Riverside, Ill., assignor to The
Imperial Brass Manufacturing Company, Chi-
cago, Ill., a corporation of Illinois

Application November 18, 1946, Serial No. 710,706

4 Claims. (Cl. 153—79)

1

The invention relates generally to tube clamping means for flaring tools or the like and more particularly to clamping means of the "in line" type.

It is a general object of the invention to provide a new and improved clamping means of the "in line" type which may be more readily and economically manufactured and which gives a sturdy, trouble-free construction.

For a flared tube to form a fluid-tight connection with a fitting or coupling as well as to have the flare conform to the standards set up by the Society of Automotive Engineers, the flare given the tube must have certain dimensions which, of course, vary with the diameter of the tube being flared. To obtain a flare of proper dimension, the tube must bear a certain relationship to the means in which it is clamped. Some users of a flaring tool through ignorance, many more through carelessness, do not clamp the tube in the proper relationship to the clamping means and a flare of improper dimension results.

It is, therefore, a further and primary object of this invention to provide new and improved tube clamping means constructed when properly utilized to assure the production of a flare of proper dimensions without any knowledge whatsoever on the part of the user of the dimensions that the flare should have.

A more particular object is to provide tube clamping means having associated therewith as a more or less permanent part thereof a gauge for determining the position of the tube to be flared in the clamping means.

As above stated, the invention relates to clamping means of the "in line" type. It relates even more particularly to an "in line" clamping means of the character disclosed and claimed in my copending application Serial No. 667,386, filed May 4, 1946, and it is a further object of this invention to provide an improved clamping means of that type.

Other and further objects of the invention will be apparent from the following specification and drawings in which

Fig. 1 is a plan view of a tube clamping means embodying my invention;

Fig. 2 is an edge elevational view of the clamping means of Fig. 1;

Fig. 3 is a longitudinal sectional view taken approximately along line 3—3 of Fig. 1; and

Fig. 4 is a transverse sectional view taken along line 4—4 of Fig. 2.

While the invention is susceptible of various modifications and alternative constructions, it

2

is shown in the drawings and will hereinafter be described in a preferred embodiment. It is not intended, however, that the invention is to be limited thereby to the specific disclosures made.

5 On the contrary, it is intended to cover all modifications and alternative constructions falling within the spirit and scope of the invention as defined in the appended claims.

As shown in the drawings for purposes of disclosure, the tube clamping means comprises generally a pair of elongated arms 10 and 11 to permit the "in line" arrangement of tube receiving bores or recesses, the actual tube clamping or gripping means herein taking the form of a plurality of blocks. Means 12 are provided for applying the longitudinal force for forcing the blocks to perform their tube clamping functions.

Referring to Fig. 1 the arms 10 and 11 are held in spaced parallel relationship by a spacing block

13, to which the arms are riveted by rivet 14. A plurality of sliding blocks 15 are mounted for sliding movement longitudinally of the arms, each block being provided with a generally rectangular channel portion 16 adapted to receive the arms 10 and 11. While the number of blocks shown is six, this is an arbitrary number and may be increased or decreased without departing from the spirit and scope of the invention. Each block 15 is generally rectangular in transverse section.

20 The blocks are slidable longitudinally of the arms and the width of the channel 16 is, for that purpose, so dimensioned as to have a sliding fit on the legs 10 and 11.

Not only are the blocks 15 all of the same lateral 35 dimensions, but they are also all of the same dimensions longitudinally, which dimensions will be termed width of the blocks. This uniformity of the width of the blocks is made possible despite the variation in size of the bores in which the

40 various sized tubes are clamped by means of the positioning and relative placement of the bores in the blocks. The bores receiving the various sized tubes are composed of semi-cylindrical and complementary recesses 17 formed in abutting

45 faces of adjacent blocks. While the recesses 17 are generally referred to as semi-cylindrical, they are actually very slightly out of round with the transverse diametric dimensions of the resulting bore a few thousandths of an inch larger than the longitudinal dimension. This prevents scoring of the tube at the lines of juncture of the two recesses.

With the exception of the end blocks which, of course, have but one recess 17 formed therein, each of the intermediate blocks has a recess

formed in each side face in order that the number of blocks required may be a minimum for the number of tube sizes capable of being clamped. This is made possible by an association of the recesses in inverse order to their relative sizes. Thus, the second block from the right, as seen in Fig. 1, has formed therein the largest and smallest recesses. The third block has formed therein the remaining smallest recess and one of the second largest recesses. The fourth block has the remaining second largest recess and one of the second smallest recesses. This arrangement is continued regardless of the number of blocks. The recesses in abutting faces of the block form, when in abutting relationship, the bores 18. As can clearly be seen in Fig. 3, the bores 18 are generally cylindrical in shape, with the exception of a countersunk portion 19 at the end of each bore. As will be noted from a close inspection of Fig. 3, the countersunk portions 19 extend into the bore a depth increasing with the size of the particular bore. For example, the countersunk portion of the largest bore at the right-hand end of the clamping tool, as seen in Fig. 3, is of greater depth than the countersunk portion of the adjoining bore. Each bore then may be considered as comprising two parts, the cylindrical portion and the countersunk portion.

The arms 10 and 11 are provided with parallel channels 20. Mounted upon the clamping means is a flare gauge 21 having a flat upper portion 22, downwardly extending side portions 23 and portions 24 extending inwardly into the channels 20. The portions 24 are so fitted into the channels 20 as to permit the flare gauge to slide in the channels longitudinally of the arms and to permit the flat upper portion 22 to be positioned over any of the bores. The flare gauge acts as a stop for a tube inserted in the bore to determine the extent to which a tube should be inserted in the clamping means in order to obtain a flare conforming to SAE standards. The distance from the cylindrical portion of the bores to the flare gauge in order to obtain a proper flare varies, of course, with the size of the tube. This variance is, in the preferred embodiment shown, taken into account by the various sizes of the countersunk portions 19. It may clearly be seen that the distance from the flare gauge to the beginning of the cylindrical portion of the bores varies for each diameter of bore. In the process of manufacture, the channels 20 are milled into the arms and the flare gauge inserted therein, and then the left-hand end of the channels (as seen in Fig. 2) are closed by deforming the same with a blow from a hammer or the like to prevent the flare gauge from sliding off the tool.

The arms 10 and 11 extend beyond the last block forming a yoke as shown. Pivotally mounted on the yoke by rivet 25 is a trunnion 26 having internally threaded portion 27 extending at right angles therefrom. A wing-bolt 28 is adapted to be threaded into the portion 27 to apply longitudinal clamping force to the blocks. By loosening the bolt 28 until the end 29 thereof is out of contact with the end block, the force applying means may be pivoted at 25 and swung to an inoperative position, permitting longitudinal sliding of the blocks for the insertion of a tube in the bores. After a tube has been inserted, the force applying means may be swung to its operative position where tightening of the bolt 28 will cause the end 29 to exert a clamping force against the end block.

It may be seen then that I have invented a tube

clamping means which is light in construction and adapted to clamp a variety of sizes of tubes. I have further provided a flare gauge which is slidable to a position over the end of a bore to provide a stop for a tube inserted therethrough which, by its position in relation to the cylindrical portion of the bore, limits the extension of a tube beyond the bore to the proper and necessary distance for forming a flare therein. During the actual flare forming operation, the flare gauge may be slid out of the way to a position where it does not interfere with the operation or may be slid out of the way while the tube clamping means is being used for purposes other than flaring.

I claim as my invention:

1. In a tube working tool a tube clamping means having a tube receiving bore, said clamping means having a guide means formed on one side thereof extending at right angles to the bore therein, and a gauge, for indicating the proper degree of insertion of a tube into the bore of the clamping means, slidably mounted on said tube clamping means to be positionable alternatively over the bore or to one side thereof, said gauge comprising a main plate portion extending at right angles to the axis of the bore, a depending portion extending parallel with the axis of the bore, and means on the depending portion engaging said guide means.

2. In a tube working tool, a tube clamping means comprising a carrier with a pair of fixed parallel sides, a pair of blocks supported by said carrier and having a tube receiving bore formed therebetween, at least one of said blocks being slidable parallel with said parallel sides and means for forcing said blocks toward one another, a guide channel in each parallel side extending at right angles to the bore between said blocks, and a gauge for indicating the proper degree of insertion of a tube into the bore of the clamping means slidably mounted on said tube clamping means to be positionable alternatively over the bore or to one side thereof, said gauge comprising a main plate portion extending at right angles to the axis of the bore, a depending portion at each end of said main plate portion extending parallel with the axis of the bore, and an inwardly extending portion on the free end of each depending portion slidably engaging in the guide channel.

3. In a tube working tool, an elongated tube clamping means having a plurality of tube receiving bores each of a different diameter and aligned longitudinally of said clamping means, one end of each of said bores having a countersunk portion, said countersunk portion increasing in depth with the increase in diameter of said bores, a guide means formed on one side of said clamping means extending longitudinally thereof and at a right angle to the axes of the bores, and a gauge for indicating the proper degree of insertion of a tube into a bore of the clamping means slidably mounted on said tube clamping means to be positionable over a selected bore to provide a stop for a tube inserted therethrough and when so positioned spacing the end of the tube from the cylindrical portion of the selected bore the proper distance for forming a flare in the tube, said gauge comprising a main plate portion extending at a right angle to the axes of the bores, a depending portion extending parallel with the axes of the bores, and means on the depending portion slidably engaging said guide means.

4. A tube clamping means for a tube working tool comprising, in combination, a pair of elongated, parallel bar members, at least six blocks

75 gated, parallel bar members, at least six blocks

all of the same width supported between said members with one of said blocks fixedly secured between said members at one end, each adjacent side face perpendicular to the general plane of said carrier of each of the intermediate blocks and the inwardly facing side faces of each end block having a generally semi-cylindrical recess formed therein extending perpendicular to the general plane of said carrier, said adjacent faces of said blocks having complementary recesses with the recesses in any one block of different size, said fixed block having a recess of intermediate size, and the successive blocks being formed with recesses of such size that the second and fourth bores considered from the fixed block become successively smaller, and the third and fifth bores become successively larger, and means closing the open end of said carrier operable to provide longitudinal force applied on a line passing through the centers of said recesses urging said blocks to tube gripping position.
